UNITED STATES PATENT OFFICE.

RICHARD H. SHADRICK, OF MINNEAPOLIS, MINNESOTA.

HEATER CONTROL.

Application filed August 26, 1924. Serial No. 734,180.

To all whom it may concern:

Be it known that I, RICHARD H. SHADRICK, a citizen of the United States, residing at Minneapolis, in the county of Hennepin and State of Minnesota, have invented certain new and useful Improvements in Heater Controls, of which the following is a specification.

This invention relates primarily to means for lighting and extinguishing heaters or burners such as are commonly used in water heating systems, and the main object is to provide an apparatus, of a novel and practical construction, in which such heater may be controlled, i. e., lighted and extinguished, from one or more points, hereinafter termed "stations", and whereby said heater, after being lighted, will be automatically "shut off" or extinguished when a predetermined amount of water has been heated. Thus, should the operator, after having lighted the heater, go away and forget to turn it off manually, he need have no fear of the consequences, as the device will automatically shut itself off, and cannot again be re-lighted until a manual release has first been effected. A number of other objects and purposes of the invention are also herein disclosed and will be fully described in the course of the following specification.

The device in question is one which is particularly adapted for use in connection with the water heating systems which are so commonly used in private dwellings and homes where a limited amount of hot water is desired at irregular intervals during the day, and although it may no doubt be adapted for use in other situations and places I have for purpose of illustration only shown it for this one purpose where it is found especially desirable and practical.

I am aware of the large number of patents and devices which have been perfected or designed heretofore, and which have for their object to provide means controlled from a distant point to regulate burners and heaters of hot water systems. These devices are for the most part of the "instantaneous" or "storage system" principle, and are either electrically or hydrostatically controlled. The chief objections to all of these devices that have come to my attention are, that they are ordinarily too expensive to manu-

facture, are too complicated and difficult to install, are impractical and require constant care and attention. Some are too expensive in their gas consumption to maintain and others are unsafe and not trustworthy enough to convince the average home owner that they have sufficient merit to warrant the cost of purchase and installation.

These and a large number of other objections to present devices which have come to my attention during several years of study and experience in this particular art, has resulted in the perfection of the apparatus which I believe has overcome at least the most common objections, and which I will now describe, with reference to the accompanying drawings, as follows:

Fig. 1 is an elevation of the major portion of the water heating system to which my device is connected, and illustrates in sectional elevation the parts of a house in which the "hook-up" is arranged.

Fig. 2 is an enlarged sectional detail view through one of my improved operating stations.

Fig. 3 is an enlarged view of the attachment proper, sectional portions being broken away for purpose of illustration.

Fig. 4 is a detail section as seen on the line 4—4 in Fig. 3.

Fig. 5 is a sectional elevation on the line 5—5 in Fig. 3.

Fig. 6 is a sectional elevation substantially similar to Fig. 5, but showing the operating arm up and the valve open.

Fig. 7 is a sectional view of the housing, as shown in Fig. 3 but with the diaphragm chamber expanded to release the valve opener.

Referring to the drawings more particularly and by reference characters A designates a water tank which is connected up in a well known manner with the coil B of a heater C by means of pipes D and E. The heater is provided with the usual burner F which is provided with gas by a pipe G. H designates the partition or wall of a first floor, such as a kitchen, while I designates the wall or partition of a second floor room such as a bath room. The sinks and other fixtures (not shown) in such rooms, to which hot water is conducted, are connected by suitable pipes with the hot water system,

as at J, while the cold water supply pipe to the hot water system is designated as K. The arrangement of parts A to K, inclusive, is of common and well known construction.

At a convenient and suitable place in the pipe G I place or insert a valve L to control the flow of gas in the pipe G to the burner F. This valve, as will later be described, is associated with a lever arm 8 in such a manner that when the arm 8 is in its lower position, as shown in Figs. 3 and 5, the valve will be closed, while if the arm is in its raised position, as in Figs. 1 and 6, the valve is open, although the valve may also be closed when the arm is raised, as indicated in Fig. 7. The arm 8 is normally and yieldingly held down by a suitable weight or other resistance 9, and is raised to its upper position by a chain or any other flexible or suitable medium 10. If the arm 8 is to be operated from only one station, as may be desired especially in one story dwellings, the chain 10 may go directly to the station. Where two stations are provided, however, as shown in Fig. 1, the chain 10 is provided with a movable pulley 11, under which is passed a second chain 12, the ends of which are respectively actuated at the two stations designated as M and N. The ends of the chain 12 are provided with rings or loops 13 and 14 to prevent the chain from being dropped through the stations, and these rings also provide convenient means whereby the chains may be manually engaged and pulled up. Pulleys 15, may be provided wherever necessary to carry the chain when the latter runs in different directions, as shown.

Each of the stations M and N, as shown in Fig. 2, consists of a plate 16 adapted to be secured on the wall, and a small cylinder or guide 17 is secured in the plate 16, to accommodate the pull chain. This guide 17 is provided with a pin 18 having a rounded end surface which is frictionally pressed against the chain by a spring 19. The pin is also provided with a finger piece 20 by which the pin may be pulled to release the chain. The spring 19 is stiff enough so that the pin 18 will hold the chain in its pulled up position against the weight of the chain and the weight 9, but will yield to a back pull which is slightly greater than that weight which is always carried. Thus, for instance, in Fig. 1 the position of the various parts indicates that the arm 8 and the weight 9 have been lifted by a pull on the ring 13 at the station M and that the chain is retained in that position by the pin 18 of that station. The pulled end of the chain indicates to the operator that the burner of the heater is lighted. Supposing, however, that a second person is in the bath room, at the station N, and also wants hot water. He

may not of course know that the burner is already lighted but may easily satisfy himself by pulling the ring 14. This movement will not affect the position of the arm 8 or chain 10, but will merely pull the chain 12 through the pulley 11 and back through the station M. Or supposing that the gas valve has been opened at station M and it is desired to close it, and extinguish the burner, at station N. In this event the operator merely pulls the ring 14 until the ring 13 stops against the station M, and then pulls the pin 18 of the station N, which action permits the weight 9 to lower the arm 8 to its inactive position. It is of course obvious that when pulling either of the rings 13 or 14 to light the heater, the resistance to the pull will be made easier if the operator will first lift the friction pin 18 with his other hand, although that is not absolutely necessary.

The valve L which is fitted into the gas pipe G is shown as of the standard and well known construction in which the valve plug 21 is yieldingly held in its closed position by a spring 22 and is adapted to be opened by a stem 23 which slidably projects, through a suitable packing joint 24, to the exterior of the valve body proper. A small valve 25, which is connected with a pilot light 26 (adjacent to the gas burner) by a tube 27, is secured to the valve L and communicates with the intake side thereof so that it may be kept burning at all times, and thus be in readiness to light the heater burner whenever the main gas valve 21 is opened.

Rigidly secured upon the casing or body of the valve L is a casting 28, having end walls or members 29 and 30, and a partition 31: and a sheet metal cover 32 is arranged to frictionally engage over the casting so as to inclose and protect the mechanism contained therein.

The mechanism just referred to is shown particularly in Figs. 3, 5, 6 and 7, and may be described as follows: Slidably journaled in the members 30 and 31 and directly over the valve stem 23 is a shaft 33, in the projecting or outer end of which is rigidly secured the arm 8. The shaft is also provided with a cam 34, which is normally positioned directly over the pin 23, and is yieldingly retained in that position by a spring 35. A suitable stop such as a washer 36 prevents the cam from being pressed inwardly past the valve stem, but as the shaft 33 is slidably journaled it may be moved outwardly until the cam misses the valve stem, as shown in Fig. 7. It will thus be readily understood that when the arm 8 is raised, from either of the stations M or N the cam 34 will press the stem 23 down until the gas valve is opened, and, that when the arm 8 is released, from either station, it will, by reason of the weight 9, return the cam to its

normal position (see Figs. 3 and 5) and allow the stem 23 to be pressed up by the spring 22 to close the gas valve L, and thus extinguish the burner.

- 5 The automatic safety or cut off device comprises a thermally responsive or expandable diaphragm chamber 37 which communicates with a container 38 through a hollow flexible wire or conductor 39. The 10 back of the container 38 is slightly curved so that it will form as complete a contact with the tank A as possible, and the receptacle is adjustably secured upon the tank by any suitable means such as a spring 40, 15 a pair of lugs 41 being provided on the container to keep it in engagement under the spring. The tube 39 is preferably flexible so that it can be readily bent around pipes or other obstructions which may be in the 20 way, and thus also permits the receptacle 38 to be moved around or up and down on the tank, as may be desired. The diaphragm 33 is adjustably secured to the end wall 29, by a nut or other suitable means 42, which acts 25 as a lock nut to lock the sleeve 43, of the diaphragm, which is screwed into the wall 29, so that an adjustment may be mechanically effected between the diaphragm and the inner end of the shaft 33. The space which 30 is sealed and confined by the hollow members 37, 43, 39 and 38 is filled or partly filled with a highly volatile or expandible liquid 44, such as ether, which is filled into the thermally responsive system through a 35 threaded hole in the receptacle 38 closed by a plug or threaded stopper 45. When in normal or idle condition, the diaphragm 37 is contracted and preferably spaced slightly from the inner end of the shaft 33, as 40 shown in Fig. 3, but, when the receptacle 38 becomes heated (by the hot water in the tank A) so as to cause the liquid therein to expand, it can only do so by expanding or extending the diaphragm, and this has the 45 effect of pressing the shaft 33 outwardly, against the tension of the spring 35, until the cam 34 moves past and allows the valve stem 23 to move up (by the spring 22) and close the valve 21, and thus extinguish the 50 burner.

The use and operation of the device may be briefly set forth as follows:

- With the various parts in their normal or inactive position, as shown in Fig. 3, 55 the operator pulls either of the rings 13 or 14 to raise the arm 8, a suitable pin or stop 46 being provided to limit the motion. This actuates the cam 34 against the stem 23 to open the gas valve L and light the burner F, as previously described. With the heater C functioning a circulation of water is effected up through the coil B and around through the members D, A and E. If warm or hot water is wanted in a short 60 time it can be drawn off through the pipe

J, almost directly from the heater. If it is not drawn as heated, however, the warm or hot water will begin to store up in the tank A, and as the cold water in the tank is circulated out through the pipe E, to be replaced by the incoming hot water the temperature of the outer surface of the upper portion of the tank will be raised, and as the volume of the hot water in the tank increases and that of the cold water 70 decreases this hot or warm area of the tank increases and moves downwardly toward the receptacle 38. Now, unless hot water is drawn off, or unless the heater is manually shut off from one of the stations M or N, the receptacle 38 being in close contact with the tank A will, when a predetermined amount of water has been heated, also become warm, and as the temperature of the fluid is raised 75 it expands the diaphragm, as previously stated, and as the cam 34 is slipped off of the valve stem it allows the valve L to close instantly, and does not shut it off gradually as the temperature of a thermally responsive element fluctuates. When the burner has 80 thus been extinguished it will follow that as no more hot water will be introduced into the tank the "temperature line" will immediately start to rise on the tank, by reason of the cooling of the water, and the diaphragm will slowly recede away from the shaft. If hot water is drawn from the tank so as to quickly cool it, it is obvious 85 that the contraction of the diaphragm will be hastened, although it is quite immaterial whether the contraction is rapid or not. 90

As the cam 34 is now pressed against the side of the valve stem by the spring 35 (Fig. 7) it is obvious that the shaft 33 cannot be returned to its normal position until the arm 8 has first been manually released, from one of the stations, so as to raise the cam, as shown in Fig. 3. If any attempt is made to light the heater, when the tank has its limit of hot water, it would of course 95 be ineffective as the cam 34 would not be in an operative position with respect to the valve stem even if the operating arm 8 was released. As the hollow wire 39 is flexibly constructed and the receptacle 38 is adjustably secured to the tank by the spring 100 40 it will be seen that the cut off level of the water may be readily adjusted without tools or instruments, and in but a moments time. It may also be stated that the manual operating mechanism of the gas valve may be utilized without the cut off device, if so desired, but to insure the water system against any danger due to overheating and to afford means for economizing in gas it is obvious 105 that the cut off feature is a very important and valuable part of the device. 110

It is understood that various suitable modifications may be made in the general design, structural details and method of 115 120 125 130

installation, provided, however, that such modifications come within the spirit and scope of the appended claims. Having now therefore fully shown and described my invention, what I claim to be new and desire to protect by Letters Patent is:

1. The combination with a hot water heating system having a gas burner, of a normally closed gas valve, a manually actuatable device including a cam co-operating with the valve for opening the same, and thermally responsive means associated with said device to disengage the cam from the valve when the latter is in an open position.
2. In a device of the character described, a yieldingly closed valve having a valve stem, a member slidably journaled adjacent to the valve and having a cam adapted to actuate said valve stem, when the member is turned, to open the valve, and means for moving the member longitudinally to dislodge the cam from the valve stem to permit the valve to close.
3. The combination with a normally spring closed valve, of a manually operable cam member arranged to open the valve, and thermally responsive means to disengage the cam member from the valve when the latter has been opened thereby, so as to effect closing of the valve.
4. The combination with a normally spring closed valve, of a manually operable cam member arranged to open the valve, thermally responsive means to disengage the cam member from the valve when the latter has been opened thereby, and means to restore the cam member to its initial operative position with respect to the valve.
5. The combination of a spring closed

valve having a projecting valve stem, a cam shaft slidably journaled near the end of the valve stem and having a cam adapted to act against the same to open the valve, means for yieldingly holding said shaft with the cam in an inactive position, and means for rotating the shaft whereby the cam will actuate the stem to open the valve.

6. The combination of a spring closed valve having a projecting valve stem, a cam shaft slidably journaled near the end of the valve stem and having a cam adapted to act against the same to open the valve, means for yieldingly holding said shaft with the cam in an inactive position, means for rotating the shaft whereby the cam will actuate the stem to open the valve, and means to move the shaft longitudinally to disengage the cam from the valve stem to effect closing of the valve.

7. The combination with a spring closed valve having a valve stem projecting therefrom, of a cam arranged, when in an initial position, to act against the valve stem to open the valve, means to laterally disengage the cam from the valve stem to effect closing of the valve, and means adapted to restore the cam to its initial position.

8. The combination with a valve having a valve stem, of a cam normally arranged in alignment with the valve stem to act thereagainst to open the valve, means for laterally disengaging the cam from the stem, and means resisting the movement of said disengaging means to restore the cam to its original position in alignment with the valve stem.

In testimony whereof I affix my signature.
RICHARD H. SHADRICK.
